UNITED STATES PATENT OFFICE.

CHARLES L. WEATHERWAX, OF ST. LOUIS, MISSOURI, ASSIGNOR TO THE UNION SPECIAL SEWING MACHINE COMPANY, OF CHICAGO, ILLINOIS, A CORPORATION OF ILLINOIS.

FOLDING-GUIDE FOR SEWING-MACHINES.

SPECIFICATION forming part of Letters Patent No. 702,512, dated June 17, 1902.

Application filed May 17, 1898. Serial No. 680,967. (No model.)

To all whom it may concern:

Be it known that I, CHARLES L. WEATHERWAX, a citizen of the United States, residing at St. Louis, in the State of Missouri, have 5 invented certain new and useful Improvements in Attachment-Holders for Sewing-Machines, of which the following is a description, reference being had to the accompanying drawings, and to the figures of reference 10 marked thereon.

My invention relates to an improvement in sewing-machines, and especially to folding devices therefor.

The object of my invention is especially to 15 provide, in connection with a cylinder or horn machine, an arrangement of folders whereby, first, in the use of one part of the device a tube, such as the sleeve of a coat, may be folded with a left-hand fold and sewed and 20 then by the use of the other part of the folder another tube needing a right-hand fold may be sewed. Thus on the same machine right and left hand sleeves may be applied to a garment by simply bringing one or the other 25 folder in position, in one case the garment itself being slipped on the tube and in the other case the sleeve.

The invention therefore consists of the combination, with a sewing-machine, of right and 30 left hand folders pivotally attached to the machine-frame and adapted to be swung down into operative position with relation to the needles, in the one case the outer edge of the folder being slightly beyond the line of the 35 outer needle, while in the other case the outer edge of the folder is beyond the line of the inner needle.

The invention is illustrated in the accompanying drawings, in which—

40 Figure 1 is a front view of a portion of a sewing-machine embodying my invention. Fig. 2 is a detail showing the attachment of the folders to the machine.

In the drawings the machine illustrated is 45 of the well-known "Union Special" cylinder-bed type, as shown in Patent No. 547,675, granted Lansing Onderdonk October 8, 1895. The needles represented are two in number and set obliquely to each other respecting the

line of the seam and coöperating with two 50 under-thread-carrying loopers.

The bed plate or cylinder of the machine is marked in the drawings 1, the overhanging arm or gooseneck 2, and the outer needle 3 and the inner needle 4. Attached by set-screws 55 to one side of the depending arm of the gooseneck is a bracket 6, upon which is pivoted the arm 7, adjustably supporting the arm or plate 8, upon the lower end of which is formed the folding-guide 9, which may be of 60 the usual construction. This is the left-hand folder, and when swung out of position the sleeve of a coat or other garment may be placed upon the cylinder, the folder swung to position, and the left-hand fold formed on 65 it, the outer edge of the folder being beyond the line defined by the outer needle-punctures, so that the fold of the sleeve and the body of the garment may be caught by both rows of stitching. Similarly attached to the 70 opposite side of the depending arm pivoted on the bracket 6 is the right-hand folding-guide 10. The two folding-guides are used separately, and the outer edge of the right-hand folding-guide is slightly beyond the line defined by the inner needle-punctures. It will 75 be noticed that these folder-supporting arms 7 are so arranged and pivoted on the plate or bracket 6 that as they swing upwardly they move outwardly away from the line of feed, 80 this result being accomplished by outwardly bending the ends 11 of the bracket 6 and pivoting the arms 7 thereto and bending the said arms 7 at the points 12, so that the lower parts of the arms 7 are bent out of parallelism with 85 the upper parts thereof. The bracket 6 has its side walls 13 and 14 downwardly converging, as shown, to firmly grasp the head of the machine.

Having thus described my invention, what 90 I claim, and desire to secure by Letters Patent, is—

1. In a sewing-machine having a suitable bed-plate, and stitch-forming mechanism, two independently movable folding-guides, one 95 right hand and one left hand, pivotally attached to the machine-frame and adapted to be swung down alternately into operative po-

sition with relation to the stitch-forming mechanism, substantially as described.

2. In a sewing-machine, having a cylindrical bed-plate, upwardly and outwardly swinging independently - movable folding-guides one right hand and one left hand pivoted to the machine-frame and adapted alternately to be swung down into operative position with relation to the stitch-forming mechanism, whereby tubular fabrics with either right or left hand folds may be sewed on the machine, substantially as described.

3. In a sewing-machine having two needles and complementary stitch-forming mechanism, and a presser-foot, two alternating swinging folders, one right hand and one left hand, pivotally attached to the machine-frame and

adapted to be swung down into operative position with relation to the needles, the outer edge of one folder when in position being slightly 20 at one side of said needles while when the other folder is swung into position its outer edge is slightly at the other side of said needles, whereby said folders when in operative position will occupy substantially the same 25 position relatively to the needles; substantially as described.

In testimony whereof I affix my signature in presence of two witnesses.

CHARLES L. WEATHERWAX.
